UNITED STATES PATENT OFFICE

ERIC SODERGREN, OF SIERRA MADRE, CALIFORNIA

WORK HOLDING DEVICE FOR MITER BOXES

Application filed April 8, 1930. Serial No. 442,629.

My invention relates to and has for a purpose the provision of a simple, substantial and inexpensive device by which lengths of material to be sawed in a miter box, can be securely held in the latter in a fixed position for sawing, thus greatly expediting the sawing operation and enabling such operation to be accurately performed, as well as preventing damage to the saw resulting from shifting of the material when the latter is sawed through.

It is a further purpose of my invention to provide a work holding device of the above described character by which material can be securely held in the miter box in close proximity to the saw irrespective of the angular position of the saw guide so that extremely short lengths of material can be accurately sawed and without any possibility that the material will become displaced during the sawing operation.

It is another purpose of my invention to provide a work holding device by which material can be sawed in a miter box at angles less than is possible with the range of adjustment provided by the adjustable saw guide of the miter box.

It is still another purpose of my invention to provide a work holding device which can be in the nature of an attachment capable of being readily applied to conventional miter boxes without modifying the construction of the latter.

I will describe only one form of work holding device for miter boxes embodying my invention and will then point out the novel features thereof in claims.

In the accompanying drawings,

Figure 1 is a view showing in plan, one form of work holding device embodying my invention, applied to a conventional miter box.

Figures 2 and 3 are views in side and end elevation respectively, of the device and miter box shown in Figure 1.

Figures 4, 5, 6 and 7 are detail perspective views of the parts comprising the work holding device.

Figure 8 is a fragmentary plan view illustrating the manner in which a relatively

short length of material is held by the device for sawing, and

Figure 9 is a view similar to Figure 8, illustrating the manner in which the device is utilized when material is to be sawed at an angle beyond the range of adjustment provided by the miter box.

Referring specifically to the drawings in which similar reference characters designate similar parts in each of the several views, my invention in its present embodiment is shown associated with a conventional form of miter box including a bed or saw table 10, from one longitudinal edge of which projects upwardly, a back rest 11 adapted to co-act with the bed in supporting a length of material for sawing by a saw 12 slidably mounted in the slotted posts 13 of a saw guide 14 pivoted at 15 on the bed for adjustment to vary the angle at which the material will be sawed, all of which is well known and will be understood by those familiar with the art.

My invention in its present embodiment comprises two holding units U and U' which are identical in construction with the exception to be later pointed out. A detailed description of one unit will suffice for both, and to distinguish like parts of the units from each other, the reference characters designating the parts of one unit are provided with exponents.

The unit U comprises a support 16 in the form of a rectangular bar secured in a horizontal position by fastening members 17-17 to the bed 10 of the miter box at one end thereof. The support is provided with a guideway 18 which is horizontally disposed and extends transversely of the length of the bed 10. The guideway is of T shaped cross section and slidably receives a carriage 19 for movement of the latter in the guideway, transversely with respect to the length of the bed. Fastening members 20-20 provided with knurled heads 21 are threaded into the support, and when tightened to engage the carriage, operate to secure the latter in a selected position of adjustment on the support.

Adjacent one end the carriage is provided with an upright extension 22 having an open-

65

100

ing 23 therethrough of rectangular cross section and extending transversely with respect to the length of the carriage. Slidable freely in the opening is a bar 24 also of rectangular cross section and forming part of a work engaging member W. A fastening member 25 provided with a knurled and slotted head 26, is threaded into the extension 22, and when tightened to engage the bar 24, 10 operates to secure the member W in a selected position of adjustment. It will thus be clear that the support 16 and carriage 19 broadly provide a mounting or a means by which the member W is rendered adjustable 15 both longitudinally and transversely of the bed, and co-act to rigidly support the member with the latter overlying the bed 10 at one side of the saw 12.

The extremity of the bar 24 which fronts the saw is provided with a horizontally disposed work engaging portion or head 27 which is rounded as indicated at 28 and projects laterally from the bar towards the back rest 11 for co-action with the latter in holding 25 a length of material on the bed 10 in a fixed position for sawing. The portion 27 is provided with a vertically disposed threaded opening 29 normally closed by a plug 30, which, when removed, permits a post 31 to 30 be threaded into the opening so as to increase the height of the portion 27 sufficiently to engage and firmly hold relatively wide material which is to be supported on the bed 10 with one side edge resting on the bed.

35 The operation of the device is as follows: With a length of material placed upon the bed 10 in the position to be sawed at a predetermined location along its length, the work-engaging members W and W', which 40 overlie the bed 10 at opposite sides of the saw, are adjusted longitudinally and transversely of the bed as required to bring their portions 27 and 27^a into firm engagement with the material in proximity to the saw 45 as shown in Figure 1. By now tightening the fastening members 20, 20^a, 25 and 25^a the members W and W' will co-act with the back rest 11 to firmly hold the material in a fixed position for sawing. It will be clear 50 that as the members W and W' can be adjusted close to the saw regardless of the angle at which the latter is disposed, that extremely short lengths of material can be securely held in a fixed position on the bed 10. Furthermore it will be noted that in instances 55 where it is desired to saw only a short section or block from an end of a length of material, as shown in Figure 1, that such short section will be firmly held against displacement by one of the members W or W'; and that in the event a length gaging member 60 such as forms part of the gaging instrument for miter boxes embodied in my co-pending application for Patent Serial No. 252,265 filed February 6, 1928, is engaging the ex-

tremity of the short section, the latter will be prevented from being rocked to an oblique position by the saw as the latter is withdrawn upon separation of the short section from the main body of the material, thereby obviating damage to the saw as well as to the sawed edges of the material. 70

From a consideration of Figure 8 it will be seen that with the saw positioned as shown in full or broken lines so as to saw a miter, 75 that the members W and W' can be suitably adjusted to firmly hold in a fixed position, a short length of material such as molding, and thus enable such short lengths to be conveniently utilized when required. 80

In the event that it is desired to saw a length of material at a less angle than is possible with the saw adjusted to either extreme angular position as shown in Figure 9, the members W and W' are removed from their respective carriages 19 and 19^a and transposed or reversed as shown in this figure, so that the member W is supported by the carriage 19^a, and the member W' by the carriage 19. As the two members are identical 90 in construction with the exception of one being right hand and the other left hand, the portions 27 and 27^a of the members will now project away from the back rest 11 as shown in Figure 9 instead of towards the back rest 95 as shown in the remaining figures.

The saw is now adjusted to its maximum angle and a previously marked length of material is placed under the saw. With the member W adjusted for its portion 27 to coact with the edge of the saw receiving slot in the back rest, in forming abutments against which the material can rest in the proper position to be sawed at the previously marked angle, the operator by now pressing the material against the thus formed abutments, can manipulate the saw to saw the material at the desired angle, as the material will be firmly supported in an oblique position with respect to the length of the bed 10. 100

When relatively wide material such as base boards with a molded side edge, are to be sawed, the material is placed upright on the bed 10 with its opposite side edge resting upon the bed, and the posts 31 are applied to the members W and W' so as to increase the height of the portions 27 and 27^a sufficient to securely hold the material in a fixed position on the bed. 110

Although I have herein shown and described only one form of work holding device for miter boxes embodying my invention, it is to be understood that various changes and modifications may be made therein without departing from the spirit of the invention and the spirit and scope of the appended claims. 120

I claim as my invention:

1. In combination, a miter box, a pair of supports secured to the bed of the miter box 130

at opposite ends thereof, and having guideways, carriages slideable in the guideways for movement transversely with respect to the bed of the miter box and having transversely extending openings therethrough, a pair of members having work engaging portions, and slidably mounted in the openings of the carriages to overlie the bed of the miter box for movement through said openings longitudinally with respect to the bed, means for securing the carriages in selected positions of adjustment, and means for securing the members in selected positions of adjustment.

2. A work holding device for miter boxes comprising a pair of work engaging members, means for mounting the members on a miter box to extend longitudinally of and to overlie the bed of the latter at opposite sides of the saw, for adjustment longitudinally and transversely of the bed, and means for securing the members in selected positions of adjustment, the members having horizontally offset work engaging portions.

3. A work holding device for miter boxes comprising a pair of work engaging members, means for mounting the members on a miter box to extend longitudinally of and to overlie the bed of the latter at opposite sides of the saw, for adjustment longitudinally and transversely of the bed, and means for securing the members in selected positions of adjustment, the members having horizontally offset work engaging portions, and posts detachably secured to said portions.

35 4. A work supporting device for miter boxes comprising a pair of supports having guideways and adapted to be secured to the bed of a miter box at opposite ends thereof to dispose the guideways transversely of the 40 length of the bed, carriages slidably mounted in the guideways, means for securing the carriages against movement, work engaging members slidably mounted in the carriages for movement transversely with respect to the 45 length of the guideways, and means for securing the members against movement in the carriages, the members having horizontally offset work engaging portions at their extremities.

50 5. A work supporting device for miter boxes comprising a pair of supports having guideways and adapted to be secured to the bed of a miter box at opposite ends thereof to dispose the guideways transversely of the 55 length of the bed, carriages slidably mounted in the guideways, means for securing the carriages against movement, work engaging members slidably mounted in the carriages for movement transversely with respect to the 60 length of the guideways, and means for securing the members against movement in the carriages, the members having horizontally offset work engaging portions at their extremities, and work engaging posts detachably secured to said portions of the members.

6. In a work holding device of the character described, a support having a guideway, a carriage slideable in the guideway, means for securing the carriage against movement, a work engaging member comprising a bar 70 slideable in the carriage transversely of the guideway and having a horizontally offset work engaging head on one extremity, and means for securing the member against sliding movement in the carriage.
